UNITED STATES PATENT OFFICE.

WESLEY F. LINDOW, OF DETROIT, MICHIGAN.

JOIST-HANGER.

No. 874,514.

Specification of Letters Patent.

Patented Dec. 24, 1907.

Application filed May 31, 1907. Serial No. 376,492.

To all whom it may concern:

Be it known that I, WESLEY F. LINDOW, a citizen of the United States of America, residing at Detroit, in the county of Wayne 5 and State of Michigan, have invented certain new and useful Improvements in Joist-Hangers, of which the following is a specification, reference being had therein to the accompanying drawings.

10 In steel construction, it is essential that parts which are used in great quantities be produced with a minimum waste of material and expenditure of time and labor.

15 The invention relates to a beam stirrup or joist hanger, which is made without special or difficult cutting of stock and which presents the necessary load sustaining properties although of simple design.

20 The invention consists in the matters hereinafter set forth, and more particularly pointed out in the appended claims.

25 Referring to the drawings, Figure 1 is a view in perspective of a hanger embodying the features of the invention. Fig. 2 is a plan view of a blank from which the hanger is struck out. Fig. 3 is a bottom view of the hanger. Fig. 4 is a view in detail of a modified form of foot for the hanger.

30 In the drawings, 1 represents the body of the hanger, which, in the initial step of construction, consists of a rectangular sheet metal blank, centrally divided or slit for a portion of its length. The arms 2 of the body formed by the split or division are divergent, and the lateral marginal portions of the body are bent forward at right angles along parallel lines spaced at a width equal to or greater than the thickness of the joist for which the hanger is intended, to form 35 flanges 3.

40 Where the angles or lines along which the flanges 3 are bent from the body, intersect the inner edges 4 of the divergent arms 2 and what may be termed the webs 5 of the 45 arms 2 disappear, the arms are bent inwardly in a plane transverse to the plane of the body, and are secured together, thus forming a horizontal foot for the hangers.

50 In the preferred form of construction these horizontal portions 6 of the arms overlap and extend across the foot of the hanger. Stiffening ribs 7 are formed up from the body of the metal in each arm and extend a short distance around the bend. Or the 55 turned ends of the arms may be brought into abutting relation, as in Fig. 4, and a rein-

forcing plate 9 laid upon them, and riveted or otherwise fastened. A convenient method of securing the parts consists in striking out and bending up lugs 10 from the ends of the 60 arms, passing them through a suitable aperture 11 in the superimposed plate and upsetting and heading the lugs down. The upper portion of the body is turned back to form a hook, and this is likewise stiffened at 65 the bend by one or more ribs 12 or the like struck out from the plate which may be situated, if desired, to give clearance for the end of the joist, the flanges 3 being preferably somewhat outwardly flared and disappear- 70 ing into the horizontal web as they pass around the bend. By this method of construction, the tensile strength of the cross-section is preserved throughout the length of the hanger, while the material is so distributed as to afford the necessary resistance to sidewise strain. The formation from the blank requires only a few steps or successive 75 handlings, and the shape of the blank is such that it is sheared from stock with no waste. 80

What I claim as my invention is:—

1. A joist hanger formed of a rectangular blank of sheet metal which is centrally divided longitudinally for a portion of its length and spread into a pair of divergent arms whose 85 outer marginal portions are bent forward at right angles on parallel lines which are continuations of the upper marginal lines of the blank, the flanges thus formed being inturned at right angles and secured together and the 90 undivided part of the blank being bent back transversely at right angles.

2. A joist hanger formed of a rectangular blank of sheet metal which is divided at one end on its longitudinal axis for a portion of 95 its length and spread into a pair of divergent arms whose outer marginal portions are bent forward at right angles on parallel lines which are continuations of the lateral marginal lines of the undivided portion of the blank, 100 and inturned at right angles near their ends and secured together, the undivided part of the blank being bent back transversely at right angles.

3. A joist hanger formed of a rectangular 105 blank of sheet metal which is centrally divided longitudinally for a portion of its length and spread into a pair of divergent arms whose outer marginal portions are bent forward at right angles on parallel lines which are continuations of the upper marginal lines of the blank, the flanges thus formed being inturned 110

at right angles and secured together and the undivided part of the blank being bent back transversely at right angles, and stiffening members formed up in the blank around the 5 transverse bends.

4. A joist hanger comprising a vertically disposed sheet metal body whose lower portion is centrally divided and spread into a pair of divergent arms, whose lateral marginal portions are bent forward at right angles to the body for flanges thereto, on spaced 10 parallel lines intersecting with the lines of the inner divergent margins, the flanges being horizontally inturned near the intersection of

15 the lines and secured together, and the body being bent horizontally back near its upper end.

5. A joist hanger formed of a rectangular blank of sheet metal which is centrally divided 20 longitudinally for a portion of its length and spread into a pair of divergent arms whose outer marginal portions are bent forward at right angles on parallel lines which are continuations of the upper marginal lines of the 25 blank, the flanges thus formed being inturned at right angles below the point of disappearance of the web of each arm into its respective flange and secured together, and the undivided part of the blank being bent trans-

30 versely at right angles.

6. A joist hanger formed of a rectangular blank of sheet metal which is centrally divided longitudinally for a portion of its length and

spread into a pair of divergent arms whose outer marginal portions are bent at right 35 angles on parallel lines which are continuations of the upper marginal lines of the blank, the flanges thus formed being inturned at right angles below the point of disappearance of the web of each arm into its respective 40 flange and secured together, and the undivided part of the blank being bent transversely at right angles, and longitudinal stiffening ribs being struck up at the transverse bends of the body and flanges. 45

7. A joist hanger comprising a vertically disposed sheet metal body whose lower portion is centrally divided and spread into a pair of divergent arms, whose lateral marginal portions are bent forward at right angles to 50 the body for flanges thereto, on spaced parallel lines intersecting with the lines of the inner divergent margins, the flanges being horizontally inturned near the intersection of the lines and secured together, and the body 55 being bent horizontally back near its upper end, said body and flanges being provided at their transverse bends with longitudinal stiffening ribs struck up from the body.

In testimony whereof I affix my signature 60 in presence of two witnesses.

WESLEY F. LINDOW.
